(57) **CLAIM**

The ornamental design for an enclosed chamber, adjustable finish-applicator for flat and dimensional surfaces, as shown and described.

DESCRIPTION

FIG. 1 is a side perspective view of the enclosed chamber, adjustable finish-applicator for flat and dimensional surfaces showing my new design;

FIG. 2 is a right side view of the enclosed chamber, adjustable finish-applicator for flat and dimensional surfaces;

FIG. 3 is a top perspective view of the enclosed chamber, adjustable finish-applicator for flat and dimensional surfaces;

FIG. 4 is an end view of the enclosed chamber, adjustable finish-applicator for flat and dimensional surfaces;

FIG. 5 is a bottom perspective view of the enclosed chamber, adjustable finish-applicator for flat and dimensional surfaces;

FIG. 6 is a bottom plan view of the enclosed chamber, adjustable finish-applicator for flat and dimensional surfaces.

FIG. 7 is a side perspective view of the enclosed chamber, adjustable finish-applicator for flat and dimensional surfaces and further illustrating an example of a flat and dimensional surface upon which the enclosed chamber, adjustable finish-applicator may act; and,

FIG. 8 is an enlarged detailed view of the side perspective view similarly demonstrated in FIG. 1.

The broken lines in the drawings depict unclaimed environmental subject matter.
